UNITED STATES PATENT OFFICE.

WILLIAM CHARLES STEPHENS, OF CORNWALL, ENGLAND.

ROCK-DRILLING MACHINE.

1,214,607.

Specification of Letters Patent.

Patented Feb. 6, 1917.

Application filed May 19, 1915. Serial No. 29,138.

To all whom it may concern:

Be it known that I, WILLIAM CHARLES STEPHENS, a subject of the King of Great Britain, residing at The Climax Rock Drill & Engineering Works, Limited, Carn Brea, Cornwall, England, have invented new and useful Improvements in or Connected with Rock-Drilling Machines, of which the following is a specification.

10 My invention relates to rock drilling machines of the hammer type. In machines of this type as now generally constructed, it is a common practice to make the drill shanks, tools, or borers of round steel, and to form 15 long wings, squares, flats or the like thereon to allow of the operation of the twisting device; such an arrangement, however, is expensive. Furthermore, when the drill shanks are made hollow for delivering 20 water to the bottom of the bore hole, a lateral hole for admitting the water has to be formed through the drill shank at some distance from the end of the latter, which 25 hole is a source of weakness when the drill is at work, and if, as sometimes occurs, the drill shank breaks, a considerable length of steel is wasted.

The object of my invention is to simplify 30 the construction of the drill shank and also, when water circulation is provided for, to arrange that in case of the fracture of the drill shank, only a short length of steel shall be wasted.

In carrying out my invention, the steel of 35 which the drill shank is constructed is flattened at the end only so as to give it the form of a chisel or punch bar with a blunt edge, or instead of making it in this manner it can be formed with one flat or with three or 40 more flats, as desired, the essential condition, however, being the formation of only the extreme end of the drill shank with one, two, three or more sides which will fit into a correspondingly shaped socket, chuck or stop 45 in the front cover of the drill and project into the drill cylinder so that it will be struck by the hammer, the said front cover being fixed so as to be rotated or oscillated with the drill and thereby correspondingly 50 rotate or drive the drill shank or tool without employing a separate rotating device attached to the tool itself. When the drill shank or borer is provided with a central hole for the flow of water, the flattening of 55 the rear end of the said borer closes the hole and seals the end to prevent the water leak-

ing back into the machine. To introduce water into the central hole in the borer a small drilled radial hole is provided as heretofore, but this radial hole is near to the flattened end of the borer so that in case of breakage at this hole, the amount of steel which is broken off will not be material, and involve much waste. In order to introduce water into the borer I combine with the 60 front cover before referred to a sleeve through which the borer has to be passed to introduce the flattened end into the chuck, the said sleeve having an opening formed in it at one side to enable it to be attached to 65 the water supply; to prevent the water from escaping around the borer I provide packing rings which fit the borer and means for adjusting the compression of such packing 70 rings.

75 My invention will be readily understood by reference to the accompanying drawings, in which:—

Figure 1 is a side view partly in section of a front portion of a drill having my improvements applied to it. Fig. 2 is a plan view of the chuck end of the drill. Fig. 3 is a view looking in the direction of the arrow, Fig. 2, and Fig. 4 is a section on the line 4—4, Fig. 1. Figs. 5 and 6 are respectively a 80 side view and an end view of the chuck detached. Figs. 7 and 8 are respectively a side view and an end view of a cam lever, and Fig. 9 is a face view of a cam plate for compressing the packing rings in the packing 85 sleeve. Fig. 10 is a sectional side view illustrating a modification in the construction of the chuck, and Fig. 11 is a plan thereof. Figs. 12 and 13 are sections on the lines 12—12 and 13—13 of Fig. 10, respectively. Figs. 90 14 and 15 are elevations at right angles of a detail. Figs. 16 and 17 are respectively a longitudinal section and an end view illustrating a further modification.

a indicates the cylinder of the drill and *b* 100 the piston or hammer reciprocating therein.

c is the front cover of the cylinder and *d*, *d* are longitudinal bolts by means of which the said cover is held in position on the cylinder, springs *e*, *e* being arranged upon 105 extensions of the said bolts between the heads and a plate *e*¹ to minimize the vibration due to the concussion of the hammer.

Referring to the arrangement illustrated in Figs. 1 to 9, *f* is the chuck which is fitted 110 into a recess in the cover *c*, the said chuck (which is shown detached in Figs. 5 and 6)

being constructed with lugs f^1 f^1 which engage in corresponding recesses in the cover c . This chuck is formed with an aperture g designed to receive the correspondingly shaped end of the borer h . As shown in Figs. 1 and 2 the end of the borer h is provided with flat surfaces similar to a chisel or punch bar, the extreme end of the said borer projecting through the chuck f so that it will be struck by the hammer b as the latter reciprocates. In the drawings I have represented the borer as being formed with only two flat surfaces. It will be obvious, however, that it may be formed with three or more such surfaces, the aperture g in the chuck being correspondingly shaped. It will be understood that with this arrangement the cost of preparing borers to fit a drill can be cheaply and expeditiously effected.

20 When provision is to be made for supplying water through the borer h the front cover c has formed integral with it a sleeve i forming a stuffing box, the gland of which is partly formed of the plate e^1 before referred to. Within this stuffing box is a ring l bored and turned so that spaces are formed between the walls of the said stuffing box and the said ring and between the ring and the borer h , a series of holes l^1 being made in the said ring to allow water which is introduced, say, through the socket l^2 , to pass into the central hole m of the borer through the lateral hole m^1 . In connection with this ring l are packing rings n , n which are preferably made concave on the outer side and convex on the inner side, as clearly shown in Fig. 1, so that when the gland e^1 is tightened up the slight compression produced thereby will cause the said rings to bulge inwardly, so as to form a tight joint around the borer h . When the pressure on the said gland is slackened, the pressure of the rings n upon the borer h is relieved so that the latter can be readily removed and replaced. In order to facilitate compressing the packing rings n around the borer h when the latter is in a position for operation, and for relieving the pressure of the said rings upon the borer when the latter is to be removed, I arrange in front of the gland a plate o , Figs. 2 and 9, forming an abutment through which the said borer is adapted to pass and fit somewhat closely, the said abutment engaging the extensions of the bolts d and being held against movement in one direction thereon by means of nuts o^1 .

Between the gland e^1 and the abutment o is arranged a cam ring p through which the borer h passes, the said ring being provided with a projecting lever handle p^1 , Figs. 7 and 8, for rotating it, and having upon one face inclined or cam surfaces q , q which correspond with cam surfaces q^1 , q^1 upon the abutment o , or upon the gland e^1 , in such a manner, that when the said cam ring is

turned in one direction, the gland will be forced by the said ring inward against the packing rings n , n , thereby compressing the latter. The movement of the cam ring p in the opposite direction will permit the gland e^1 to move out again under the pressure of the springs e or of springs otherwise arranged. In practice the cam surfaces q^1 , q^1 are preferably so formed that the ring p locks itself in position when the gland is forced fully home.

Instead of, or in addition to, the cam ring p before described, I may construct the nuts o^1 which secure the abutment o , or the gland e^1 , upon the bolts d , d with ribs r , r which engage with corresponding grooves on the face of the said abutment, this construction allowing of the ready adjustment of the nuts while at the same time preventing them from working loose under vibration.

85 In order to compensate for the wear due to the continual vibration to which the borer h is subjected so that it will be caused to project to a uniform extent through the chuck or stop f and also to provide for positioning the said borer in case one side of the said chuck or stop wears more than the other, I sometimes construct the chuck with movable jaws or blocks, according to the number of flats formed upon the borer, the said jaws 90 or blocks being adjustable in a radial direction with relation to the axis of the borer h , the faces of the blocks with which the flats of the borer come in contact being inclined to correspond with the inclination of the said flats. This modification is illustrated in Figs. 10 to 15, s , s being the jaws or blocks which form the socket into which the end of the borer h fits. These blocks s are located in a transverse groove or recess formed in the end 105 of the cover c adjacent to the cylinder a and are arranged with their inclined faces opposite to one another so that the tapered end of the borer h can be introduced between them. On opposite sides of the cover c are arranged plates t , t through which screw-threaded studs or shanks s^1 , s^1 on the said jaws or blocks s project, the blocks being securely fixed to the said plates, for instance, by nuts t^1 , t^1 so as to be adjustable therewith. 110 These plates are carried by bolts u , u passed through the cover c from side to side so that they are common to both plates t , whereby the tightening of nuts u^1 , u^1 upon the said bolts will adjust both plates t and consequently the jaws s , s simultaneously. The adjusting nuts u^1 , u^1 are preferably formed on their under surfaces with ribs which coöperate with notches on the adjacent plate t (as hereinbefore described with reference to the nuts o^1 in the bolts d) so that they can be readily adjusted, and springs v , v are arranged between the said plates t and the cover c , the action of which springs is to press the said plates against the 115 120 125 130

nuts u^1 , u^2 . As a further modification of the arrangement for compensating for wear of the flat surfaces due to the continual vibration, I form through the cover c two parallel slots which intersect the central recess therein and having their inner or adjacent surfaces in planes corresponding with the planes of the flats or inclined surfaces on the borer h , and into these slots I insert strips 10 w , w of steel or other suitable metal which will constitute the flats of the chuck, as clearly shown in Figs. 16 and 17. These strips are connected at their outer ends by keys x , x or by other suitable means so as to prevent them from falling out of position, to allow of their being shifted from time to time to bring fresh surfaces into position for contact with the head of the borer as may be required.

15 Having now fully described and ascertained my said invention and the manner in which it is to be performed, I declare that what I claim is:—

20 1. A rock drilling machine comprising a working cylinder provided with a chuck having a flat surface inclined to the longitudinal axis of said cylinder, a hammer piston mounted in said cylinder, and a drill bit mounted in said chuck and provided at its inner end with a flat inclined surface in engagement with the flat surface of the chuck,

25 2. A rock drilling machine comprising a working cylinder provided with a chuck having an adjustable member provided with a flat surface inclined to the longitudinal axis of said cylinder, a hammer mounted in said cylinder, and a drill bit mounted in said chuck and provided at its inner end with a flat inclined surface in engagement 30 with the flat surface of the chuck.

35 3. In a rock drilling machine, the combination with a working cylinder, of a hammer piston mounted in said cylinder, a front cover secured to the working cylinder and provided with a chuck having a flat surface inclined to the longitudinal axis of the cylinder, and a drill bit mounted in said cover and provided at its inner end with a flat inclined surface in engagement with the inclined surface of the chuck.

40 4. In a rock drilling machine, the combination with a working cylinder capable of a rotating or oscillating movement, of a hammer piston mounted therein, a front cover secured to said cylinder and provided with a chuck having a flat surface inclined to the longitudinal axis of the cylinder, and a drill bit mounted in said cover and provided at its inner end with a flat inclined surface in

engagement with the flat inclined surface of 60 the chuck.

5. In a rock drilling machine, the combination with a working cylinder, of a hammer piston mounted therein, a front cover secured to the working cylinder and provided with a chuck having a flat surface inclined to the longitudinal axis of the cylinder, a drill bit mounted in said cover and provided at its inner end with a flat inclined surface in engagement with the inclined surface of the chuck, a stuffing box formed integral with the cover, packing mounted in said stuffing box and surrounding said bit, and means for compressing said packing in said stuffing box for holding said bit in engagement with the chuck.

6. In a rock drilling machine the combination with a working cylinder, of a hammer mounted therein, a cover fixed to said cylinder and provided with a chuck having a flat surface inclined to the longitudinal axis of the cylinder, a drill bit mounted in said cover and having its inner end provided with a flat surface in engagement with the flat surface of the chuck, a stuffing box also provided on said cover, packing arranged in said stuffing box and surrounding said bit, a gland for the stuffing box, and means for moving said gland with relation to said stuffing box to compress said packing 90 for holding the bit in engagement with the chuck.

7. In a rock drilling machine, the combination with a working cylinder capable of rotating or oscillating movement, of a hammer mounted in the same for reciprocating movement, a cover secured to said cylinder by bolts and provided with a chuck having a flat surface inclined to the longitudinal axis of the cylinder, a stuffing box integral 100 with said cover, a drill bit passing through said stuffing box and having its rear end provided with a flat inclined surface for engagement with the flat surface of the chuck, packing provided in said stuffing box, a gland adapted to coöperate with said stuffing box, a plate mounted on said bolts and having a cam surface, springs mounted on said bolts between the gland and cover, and a cam member having a cam surface adapted 105 to coöperate with the plate cam for moving said gland into the stuffing box and compressing the packing.
